GAS OR VAPOR FILLED DISCHARGE DEVICE

Hans Vatter, Berlin-Charlottenburg, Germany,
assignor to Siemens & Halske, Aktiengesellschaft, Siemensstadt, near Berlin, Germany, a
corporation of Germany

Application September 30, 1936, Serial No. 103,297
In Germany October 5, 1935

3 Claims. (Cl. 250—27.5)

My invention relates to electrode structure, and especially to electrode structure for gas or vapor filled discharge devices.

An object of the invention is to provide a cathode structure that will permit a quick change from a glow to an arc discharge at comparatively small current strengths.

It is well known that in a gas or vapor filled discharge device the discharge first becomes a glow type which is later transformed into an arc type of discharge in most cases the smallest arc current magnitude is considerably larger than the current magnitude of the glow discharge. It is desired to provide a special type of electrode for causing the arc discharge to be established quickly at comparatively small current strengths.

Other objects and advantages of the invention will be apparent from the following description in conjunction with the accompanying drawing 20 in which the figure illustrates a discharge device with a preferred embodiment of the electrode structure.

In its specific embodiment, my electrode structure has two portions, one of which 10 has the large surface which may be, as illustrated, the bottom of an inverted cup. This large active surface portion has preferably a central opening 11 therein through which projects a stem 12 having on its projecting portion a pointed portion 13. This stem is connected at 14 to the cup supporting the other portion 10 of the electrode structure at a considerable distance from the pointed end 13. The continued extension 15 of this stem 12 may be utilized as a lead support 35 and there may be additional supporting elements such as the stem 16.

The complete device, of course, includes at least one other cooperating main electrode and, if desired, control and auxiliary electrodes of 40 any desired shape and arrangement.

In the operation of the device, the glow discharge heats the projecting point to a high temperature and thus makes possible the speedy transition to an arc type of discharge that will spread to the large active surface of the portion 10. The higher temperature of the point depends upon the fact that effective heat conduction can only take place from the point along the wire 6 and as this is only a small surface, the radiation loss is as small as possible. This 50 heat transference from the pointed portion 13 may be minimized in various ways if desired. The portion 12 may be of poor heat conducting material or may be designed with a very small

cross section intermediate the pointed portion 13 and the connecting place 14 to the large surface electrode portion 10. This connecting portion may, for example, be of a small tungsten wire coated with insulation such as glass or porcelain. The intermediate portion 12 might contain a section of graphite that would conduct electricity readily, but not heat.

The point 13 may have a diameter of about 1 millimeter and preferably projects only but one- 10 half millimeter above the surface.

The pointed portion 13 may, of course, be constructed if desired of material that would readily start the discharge such as nickel, tungsten, or other materials with caesium, barium, thorium 15 incorporated therein or on its surface.

While a specific embodiment of the invention has been disclosed, it is apparent that many modifications thereof are possible. Accordingly the appended claims are not to be limited except 20 insofar as is necessitated by the prior art.

I claim as my invention:

1. An electrical discharge device comprising a container, a gaseous atmosphere therein, an anode and a cathode structure within said container, said cathode structure having a large surface facing said anode and having an opening 25 therein, a stem of said cathode structure projecting through the opening in said surface, said stem and said large surface being connected together away from the discharge space between said anode and cathode.

2. An electrical discharge device comprising a container, a gaseous atmosphere therein, an anode and a cathode structure within said container, said cathode structure comprising a cup-shaped portion and a stem portion, said cup-shaped portion having a surface facing said anode with a rim portion extending away from 35 said anode, said stem portion projecting through 40 an opening in the surface of said cup-shaped portion.

3. An electrical discharge device comprising a container, a gaseous atmosphere therein, an anode and a cathode structure within said container, said cathode structure comprising a cup-shaped portion and a stem portion, said cup-shaped portion having a surface facing said anode with a rim portion extending away from 45 said anode, said stem portion projecting through 50 an opening in the surface of said cup-shaped portion, and connected to the inner side of said rim portion.

HANS VATTER.
